UNITED STATES PATENT OFFICE.

FRANCIS J. THUMAN, OF BALTIMORE, MARYLAND.

HULL OF WATER-CRAFT.

1,312,369.

Specification of Letters Patent.

Patented Aug. 5, 1919.

Application filed May 4, 1917. Serial No. 166,282.

To all whom it may concern:

Be it known that I, FRANCIS J. THUMAN, a citizen of the United States, residing at Baltimore, in the State of Maryland, have 5 invented certain new and useful Improvements in Hulls of Water-Craft, of which the following is a specification.

This invention relates to improvements in hulls or bodies of water craft, such for example as yachts, merchant or naval vessels, and is especially applicable to craft of light draft where speed is a desideratum.

One object of the invention is to provide an improved construction of hull or body 15 that will practically eliminate the formation of a vacuum beneath the bottom or at the stern of the hull when the vessel is being driven ahead.

Another object of the invention is to provide improved means for conveying air to 20 and along the bottom of the hull, between the latter and the water, whereby to form a cushion and a lubricant that will materially overcome friction and produce a greater speed with the least expenditure of energy.

A further object of the invention is to provide an improved hull structure, embodying the features above set forth, and at the same time be seaworthy and stable.

30 The means for driving the craft is not essential to the present invention and therefore is not illustrated, but may consist of one or more propellers driven by any well-known or approved means, such as gasolene, steam or electricity as preferred.

The invention is illustrated in the accompanying drawing, wherein,—

Figure 1, shows in side elevation a craft, whose hull embodies the present invention.

40 Fig. 2, illustrates the same in inverted or bottom plan.

Fig. 3, shows the same in vertical longitudinal section.

Fig. 4, illustrates a vertical cross-sectional detail as the same would appear if taken on the line 4—4 of Fig. 1, looking in the direction of the dart.

Fig. 5, shows another cross-sectional detail through the craft as would appear if 50 taken on the line 5—5 of Fig. 1.

Fig. 6, illustrates a similar sectional view through the craft if taken on the line 6—6 of Fig. 1, looking in the direction of the dart, and

55 Fig. 7, shows the craft in rear or stern elevation.

In the illustrated exemplification of my invention little importance is placed on the formation of deck 8, and the superstructure 9, of the craft as these may be varied to 60 meet the requirements or use for which the craft is intended.

The hull or body structure is, however, important, in that it embodies the inventive idea in one practical form.

65 The sides 10, of the hull are formed on concave lines, in a vertical direction, and are so designed, to cast aside, or displace, the water with the least amount of resistance.

70 The bottom 11, of the hull is narrowest at the stem or bow 12, and broadens as it extends from stem to stern, at which latter point it is preferably broadest.

75 The keel 13, in the present instance, increases in depth from stem to stern and materially adds stability and sea-worthiness to the craft.

80 At each side of the keel, the bottom is concave, as at 14, which concavities are narrow and of greater depth at the stem, and diminish in depth and increase in width as they extend toward the stern.

85 The stern 15, of the craft inclines rearwardly and downwardly from the deck 8, and consists of a plane surface having for 90 its upper edge, one irregular curve, and for its lower edge two irregular curves, which results in the bottom of the hull at the stern extending rearwardly beyond the deck as clearly indicated by the broken lines in the bottom plan view of Fig. 2.

An air tube 16, is provided at the stem or bow with its upper end 17, opening forward above the deck 8, and its lower end 18, communicating with the narrow and deep forward ends of the concavities 14, that extend along the under side of the hull. A valve 19, is provided in the air tube for the obvious purpose of controlling the passage of air to 100 the said forward ends of the concavities.

At the stern, the improved craft is provided with another air pipe 20, having an upper end 21, projecting above the deck 8, and also opening forward, and a lower end 105 22, which spreads laterally and has openings 23, at the edge formed by the inclined stern and the bottom. This air pipe 20, is also provided with a valve 24, to control the passage of air therethrough.

110 The construction of the hull-bottom is such that the propeller 25, may be readily

located below the stern air-discharge openings 23, as indicated in Fig. 3, of the drawing.

By reference to Fig. 3, it will be seen that 5 the concave bottom surfaces start at the lower end 18, of the air tube 16, and from this common point extend rearwardly, gradually flattening or decreasing in depth and increasing in width as they extend rearwardly, and that for a comparatively short 10 distance from the rear or stern end the opposite edges of the bottom are parallel, as at 26, and as nearly parallel to the water line 27, as possible.

15 From the foregoing explanation it will be understood that the two main forces to be overcome, to wit: the displacement of the water as the craft moves forward, and the resisting force produced by the formation of 20 a vacuum at the stern, are both met as the result of my structure. The concave formation 10, of the sides, overcoming the first, and the concave formation of the bottom, plus the forward and rear air-supply pipes meeting 25 the second force.

Having described my invention what I claim is,—

1. A water craft having a hull with center

30 keel from stem to stern and whose bottom surface is provided with concavities at 35 opposite sides of the center keel said concavities at the forward end forming grooves whose outer edges are substantially as low as the bottom edge of the keel and decrease in depth and increase in width as they extend 35 toward the stern, and means at said deeper and narrower ends of the grooves for supplying air to the latter.

2. A water craft having a hull with a 40 deck and provided with center keel, the bottom of the hull spreading and increasing in width from a point near the bow toward the stern and from the stern the bottom having parallel side edges that extend forward 45 to and merge with the spreading portions of the bottom the parallel side edge portion of the bottom projecting rearwardly of the deck and means for discharging air from the projecting stern portion at a point below the water line.

50 In testimony whereof I affix my signature in the presence of two witnesses.

FRANCIS J. THUMAN.

Witnesses:

CHARLES B. MANN, Jr.,

JOHN E. O'NEILL.
